UNITED STATES PATENT OFFICE

2,640,602

CUSHIONING MECHANISM FOR RAILWAY VEHICLES

Donald Willison, Cleveland, Ohio, assignor to National Malleable and Steel Castings Company, Cleveland, Ohio, a corporation of Ohio.

Application September 1, 1950, Serial No. 182,749.

20 Claims. (Cl. 213—45)

1

This invention relates to draft gears or cushioning mechanism for use on railway vehicles and more particularly to a draft gear made up of groups of compression rubber pads, and metallic followers so arranged as to produce a draft gear of the compensating type.

In the copending patent applications of Hubert L. Spence and Donald Willison, Serial No. 688,174, filed August 3, 1946, and Donald Willison, Serial No. 150,473, filed March 18, 1950, are disclosed cushioning mechanisms of the above mentioned compensating type which automatically compensate for inequalities in the length of the draft gear pocket in the railway car and of the yoke which surrounds the cushioning mechanism. This automatically eliminates any free slack between the yoke, draft gear and draft gear pocket, which with a non-compensating type of draft gear would be present.

The present invention provides various features and improvements over compensating type of cushioning mechanism disclosed in the above-mentioned applications.

The various features and advantages of the invention will be set forth in the accompanying description taken in conjunction with the drawings in which:

Fig. 1 is a plan view, partly in section of a compensating draft gear embodying my invention, the mechanism being applied to a conventional freight car structure using the A. A. R. standard vertical plane horizontal key yoke.

Fig. 2 is a side elevational view of the mechanism shown in Fig. 1.

Fig. 3 is a plan view showing the first stage of compression of the draft gear from a light buffering force.

Fig. 4 is a plan view showing the second stage of compression resulting from a heavier buffering force.

Fig. 5 is a typical compression curve illustrating the draft and buffering characteristics of the cushioning mechanism shown in Figs. 1 to 4.

Fig. 6 is a perspective view of one of the cushioning followers of the cushioning mechanism, with a portion of the yoke shown in dot-dash lines.

Fig. 7 is a perspective view of one of the compensating followers of the cushioning mechanism.

Fig. 8 is an end elevational view of the cushioning follower showing the manner of assembling the follower into the yoke.

Fig. 9 is a plan view partly in section of a modified form of the invention.

Fig. 10 is a side elevational view, partly in section, of the modification shown in Fig. 9.

2

Fig. 11 is a plan view, partly in section, of another modification of the invention.

Fig. 12 is a side elevational view of the modification shown in Fig. 11.

Fig. 13 is a typical compression curve illustrating the draft and buffering characteristics of the cushioning mechanism shown in Figs. 11 and 12.

The form of the invention shown in Figs. 1 to 8 inclusive is intended primarily for railway freight car service or for use on switching locomotives which are generally built with the standard A. A. R. type of draft gear pocket. In the drawings are shown the spaced center sills 10 of a car, and a draft gear pocket 12 formed by the sills, the front draft lugs or stops 14 and the rear buffering lugs or stops 16. The conventional striking casting 18 is secured to sills 10, the inner ends of the casting forming the front stops 14 of the draft gear pocket. The yoke 20 is an A. A. R. standard vertical plane horizontal key yoke, known as the Y-40. The shank 22 of the car coupler is connected to the yoke by the horizontal key 24 of conventional construction which extends laterally through slots 26 in the center sills 10 and in side walls 28 of the striking casting. Slots 26 are of sufficient length that the ends thereof are at no time engaged by key 24 during draft and buffering movements of the coupler and yoke. Slot 30 in the coupler shank is preferably of slightly greater length than the width of key 24, leaving a clearance as at 32 between the key and the forward end of the slot when the mechanism is in neutral position, as in Fig. 1.

In engagement with the front and rear stop lugs 14 and 16 are the cushioning followers 34 of the draft gear. Compressed between transverse abutment walls 36 of the cushioning followers is a group 37 of rubber pads 38 which form the main or central cushioning unit of the gear, each pad consisting of a metal plate to which a cushion of rubber has been bonded. The surface of the rubber is corrugated, as I have found that a cushioning pad of that type combines very desirable compression qualities with a high degree of durability and sturdiness. The construction and functioning of this pad is set forth and claimed in the copending application of Donald Willison and Hubert L. Spence, Serial No. 138,614, filed January 14, 1950.

Carried by each cushioning follower 34 is a compensating follower 40 and between each compensating follower and the transverse wall 36 of the cushioning follower is another group 42 of rubber pads 38.

Each cushioning follower 34 as best shown in Fig. 6 comprises the aforementioned transversely extending wall or base portion 36 and a pair of rectangular loop portions 44 disposed adjacent sills 10. Portions 44 are formed by spaced horizontal load transmitting arms 46 which extend from base 36 at the lateral extremities thereof, and by the vertical connecting portions 48 having draft lug engaging faces 49.

Within loop portions 44 of each cushioning follower is disposed the compensating follower 40, which as shown in Fig. 7 comprises a base portion 50 and a yoke or coupler butt engaging portion 52 spaced from base 50 by webs 54. The dimensions of the compensating follower are such that it may be passed transversely through the loops of the cushioning follower during assembly of the mechanism. When outer portions 50a of the compensating follower are in engagement with the inner surfaces 56 of portions 48 of the cushioning follower, as seen on the right side of Fig. 4, the distance between surface 58 on base 50 and surface 60 of wall 36 is slightly greater than the thickness of the group 42 of compensating pads in their unloaded position. This permits easy assembly of the compensating pads between the compensating follower and the cushioning follower.

It will be observed that the horizontal arms 46 of each loop portion 44 are spaced apart vertically a sufficient amount to permit the use of the same dimension rubber pads in the compensating units of the mechanism as in the central unit so that a greater cushioning capacity is obtained than if smaller sized pads were used in the compensating units. This arrangement is made possible, without decreasing the strength of cushioning follower 34, by overlapping the sides of the yoke straps 62 with arms 46 of the cushioning follower. Thus, in effect the yoke straps 62 are recessed into the cushioning follower.

The draft gear is assembled in the yoke as follows: The rear cushioning follower 34 is inserted between the yoke straps 62 in the manner shown in Fig. 8 and then rotated into proper position. The associated compensating follower 40 is then inserted transversely through the loops 44 of the cushioning follower and moved rearwardly until its portions 50a engage surfaces 56 on the cushioning follower. One group 42 of compensating rubber pads is then inserted between the compensating follower and the cushioning follower, and this assembly is moved to the rearward end of the yoke. The other cushioning follower is similarly inserted into the yoke, its associated compensating follower inserted into place, and the two followers, without any rubber pads between them are moved to the front end of the yoke. Next the central group 37 of cushioning pads is inserted between the two cushioning followers, and the assembly of yoke and draft gear, minus the second group of compensating rubber pads is placed upright in a press, supported on the rear end of the yoke. Pressure is applied to the stop lug engaging faces 49 of the front cushioning follower sufficient to compress the central group and rear compensating group of pads until the overall length of the draft gear as measured over faces 49 of the front and rear cushioning followers is slightly less than the length of the draft gear pocket, which is 24½ inches in the case of the standard A. A. R. draft gear pocket. The front group of compensating rubber pads may then be freely inserted between the front compensating and cushioning followers. While

the assembly is held in the press, metallic slugs or other suitable fillers may be inserted between the yoke and one of the compensating followers to hold the draft gear compressed. The draft gear and yoke may then be removed from the press and the assembly can readily be raised up into the draft gear pocket in the car, after which the usual yoke or gear support plate 64 may be secured to the car sills 10.

The location of the assembly slugs will depend upon the type of yoke that is used. In the case of the Y-40 yoke shown in Figs. 1 to 4 the slugs may be applied between the rear edges 66 of the yoke hood and the shoulders 67 on central web 54 of front compensating follower 40, as illustrated in dot-dash at 68 in Fig. 4. This allows the coupler shank and coupler shank key to be freely inserted, thus completing the application of the draft gear. When the gear receives a buffing blow in service the slugs are released and are free to drop out of the assembly.

In my compensating draft gear it is important that the number of rubber pads for each group be so selected and the distances between the various followers be so maintained that in its assembled position as shown in Fig. 1, each of the groups of compensating rubber pads is under less precompression than the group of central cushioning pads. While I have shown the equivalent of 3 pads in each compensating group and the equivalent of 8 pads in the central group, it is to be understood that this is merely for the purpose of illustration and may be varied as desired, depending upon the characteristics of the pads used. The precompression for each group of compensating rubber pads may be about 7500 pounds, for instance, and that of the central or main cushioning pads about 25,000 pounds. These particular values may be varied over a considerable range, the essential requirement being that such nominal values be chosen that under all conditions of manufacturing dimensional tolerances the main cushioning group should have more precompression than the compensating groups. Some settling or "flow" of the rubber must be expected, and allowances must of course be made accordingly in order that desired values of precompression for the groups of pads be attained.

When my compensating draft gear is assembled and applied to a car, the main cushioning group 37 of rubber pads 38 presses the front and rear cushioning followers 34 firmly against the front and rear stop lugs 14 and 16, thus holding the draft gear tightly in the draft gear pocket. At the same time the compensating groups 42 of pads 38 press the compensating followers 40 tightly against the rear abutment 78 of the yoke and against the forward abutment, which in the construction shown in Figs. 1 to 4 is formed by the end surface 72 of coupler butt 22. It is to be understood that in other yoke constructions which may be used the forward abutment may be formed by an integral portion of the yoke or by a separate buffering block 88, as shown in Figs. 9 and 10. The draft gear is thus held tightly in the yoke even though there may be considerable difference between case of the Y-40 yoke shown in Figs. 1 to 4 the coupler shank 22 is pressed tightly against the draft key 24, thereby eliminating any slack between the coupler and yoke, and automatically compensating for key, key-slot, and coupler butt wear.

The operation of the mechanism is as follows: When a buffing load is applied to the draft gear,

the initial action is such that the forward compensating group 42 of pads is compressed while the rear compensating group expands, as shown in Fig. 3, the main cushioning group 61 remaining stationary. During this part of the action the yoke may be said to "float" between the two compensating groups, and the draft gear responds readily to all changes in coupler forces transmitted thereto. As the buffing load increases the forward compensating group continues to compress and the rear group continues to expand. As this action continues the resistance of the front group increases to the point where it equals the precompression under which the main cushioning group of pads is assembled. Thereafter, as the buffing load increases the main cushioning group compresses in series with the front compensating group, as shown in Fig. 4, in which it is seen that the front cushioning follower 34 has left contact with draft stops 14. This series action continues until the buffing shock is cushioned. It will be observed in Fig. 4 that the rear group of compensating pads has expanded to its normal uncompressed height, this condition occurring shortly after the series action commences. It will be noted that only the rubber pads resist the buffing load regardless of its intensity, there being no stops or abutments in the mechanism to limit the compression of the pads.

The action of the draft gear under pulling loads is the same as described above, but of course in the opposite direction.

The compression curve shown in Fig. 5 illustrates the action described above. From the zero or neutral position to the point "A" in either a buff or draft direction, only the compensating pads are functioning, one group compressing and the other group expanding. From point "A," in either direction to the end of the gear travel the main cushioning pads and one group of the compensating pads compress in series. The compensating pads and the main cushioning pads in my draft gear are preferably all alike as each pad is subjected to the same amount of load when the main group and a compensating group are being compressed in series.

I have shown the end pads in each group as formed with rubber on only one side of the metal plate, whereas in the other pads rubber is bonded to each side of the plate. By this construction I avoid any metal-to-rubber contact. The end pads may be held in place against the followers by small metal dowels 14 on the metal plates entering recesses in the followers. The pads are held in alignment with one another by means of rubber projections 16 on one pad entering into aligned recesses in the adjacent pad.

The modification shown in Figs. 9 and 10 is intended primarily for use on passenger equipment cars where a draft gear of "softer" cushioning characteristics and less capacity is desirable. In this arrangement the coupler shank 22a is shown connected to the yoke 80 for universal movement with respect thereto by means of an intermediate member 82. The coupler shank is connected to member 82 by means of a vertical pivot pin 84 while member 82 is connected to the yoke by a horizontal pivot pin 86. A buffing block 88 which engages the cylindrically curved end surface 89 of member 82 forms the forward abutment in the yoke for the draft gear. It will be observed that the cushioning followers 90 are of lesser height than the spacing of the yoke arms so that they can be assembled directly into

the yoke in a lateral direction. The two rectangular loops 92 which extend from the base 94 of the cushioning follower are tied together by integral top and bottom walls 96 which help to carry some of the draft and buffing loads to the front and rear stop lugs 14a and 16a, respectively. Walls 96 are reinforced by the transverse inwardly directed flanges 98. In the present construction the inner corners of vertical elements 102 of loops 92 have been chamfered as at 104 to allow clearance adjacent the flared reinforcing portions 106 of webs 108 on compensating followers 110. This clearance permits unrestricted movement of followers 110 outwardly of cushioning followers 90 during expansion of the compensating rubber pads. Thus outward movement of the compensating followers is limited only by the engagement of lateral portions 112 with surfaces 114 on vertical elements 102 of the cushioning followers. The rubber pads are of less width than in the previous embodiment in order that they can be inserted into the loops 92 of the compensating followers. Also the pads in the main cushioning group 116 are identical with those in the compensating groups 118. The operation of this modification is the same as that of the previous construction.

In Figs. 11 and 12 is shown another modification in which the front cushioning follower 120 is made longer than the rear cushioning follower 122. This allows the use of a greater number of rubber pads in the front group of compensating pads than in the rear group. It is also necessary to lengthen front compensating follower 124 to allow a greater clearance between this follower and front cushioning follower 120 as at 126, thereby facilitating assembly of the pads in the cushioning follower. When clearance 126 is taken up through movement of compensating follower 124 forwardly of cushioning follower 120 during assembly, the distance between base 128 and base 130 of the compensating and cushioning followers, respectively, is slightly greater than the thickness of the front group of pads so that the pads may be freely applied in place.

In Figs. 11 and 12 for purposes of illustration there are shown the equivalent of 6 pads in the forward compensating group and the equivalent of 2 pads in the rear group. The central group also has the equivalent of 6 pads. In this manner I provide a "selective travel" form of compensating draft gear which operates in the same manner as the previously described forms except that a greater number of rubber pads are available to cushion the buffing forces, than are provided for resisting the draft forces. Thus the cushioning capacity of the gear in buff is greater than in draft.

Fig. 13 shows a typical compression curve for this type of draft gear and indicates a draft travel of $1\frac{1}{2}$ inches and a buffing travel of $2\frac{1}{2}$ inches. Preferably the central group of rubber pads is compressed to a load of 25,000 pounds upon assembly of the gear in the draft gear pocket, while the front and rear groups of compensating pads are each compressed to a load of 10,000 pounds.

It will be apparent that in buff the front compensating group of pads and the central cushioning group will serve to cushion the load. In draft the rear compensating group of pads and the central group will serve to cushion the load. As in the previous forms of the invention all of the loads regardless of their intensity are

cushioned by the rubber pads, there being no metallic stops to engage and preclude further compression of the pads.

The terms and expressions which I have employed are used in a descriptive and not a limiting sense, and I have no intention of excluding such equivalents of the invention described, or of portions thereof, as fall within the purview of the claims.

What I claim is:

1. A draft gear for railway vehicles, comprising a pair of longitudinally spaced followers, a cushioning unit extending between said followers and being compressible upon movement of one of said followers toward the other, each of said followers comprising a pair of longitudinally extending loop portions positioned to engage the stop lugs of a draft gear pocket, and other cushioning units extending into and carried by said loop portions, said other cushioning units each being compressed between one of said followers and an abutment of an associated draft gear yoke for maintaining said draft gear in tight engagement with said yoke.

2. A draft gear for railway vehicles comprising a pair of longitudinally spaced followers, a cushioning unit extending between said followers and being compressible upon movement of one of said followers toward the other, each of said followers comprising a pair of rectangular longitudinally extending loop portions positioned to engage the stop lugs of a draft gear pocket, a compensating follower at each end of said gear having a transverse portion for engagement with the adjacent abutment in a draft gear yoke, said compensating follower being carried by the loop portions of the associated one of said first-named followers and being movable longitudinally thereof, and a compensating cushioning unit carried by said loop portions and being compressible upon movement of said compensating follower inwardly of the associated one of said first-named followers.

3. A draft gear for railway vehicles comprising a pair of longitudinally spaced followers, a cushioning unit extending between said followers and being compressible upon movement of one of said followers toward the other, each of said followers comprising a base portion in engagement with an end of said cushioning unit and a pair of rectangular loop portions extending longitudinally from said base portion and positioned to engage the stop lugs of a draft gear pocket, a compensating follower at each end of said gear having a transverse portion for engagement with the adjacent abutment in a draft gear yoke, said compensating follower being carried by said loop portions of the associated one of said first-named followers and being movable longitudinally thereof, and a compensating cushioning unit at each end of said gear carried by said loop portions, each compensating unit reacting between said base portion of the associated first-named follower and said compensating follower to oppose movement of the latter toward said base portion.

4. A draft gear for railway vehicles comprising a pair of longitudinally spaced followers, a cushioning unit extending between said followers and being compressible upon movement of one of said followers toward the other, each of said followers comprising a base portion, vertically spaced arms extending in one direction longitudinally from the lateral extremities of said base portion, and a vertical portion joining the ends of

said vertically spaced arms positioned to engage the stop lugs of a draft gear pocket, a compensating follower at each end of said gear having a transverse portion for engagement with the adjacent abutment in a draft gear yoke, said compensating follower having portions extending between said arms and being movable longitudinally thereof, and a compensating cushioning unit at each end of said gear and extending between said arms, said compensating cushioning unit reacting between said base of the associated first-named follower and said compensating follower to oppose movement of the latter toward said base portion.

15 5. A draft gear for railway vehicles comprising a pair of longitudinally spaced followers, a cushioning unit extending between said followers and being compressible upon movement of one of said followers toward the other, each of said followers comprising base portion and a pair of laterally disposed rectangular loop portions extending longitudinally from said base portion and positioned to engage the stop lugs of a draft gear pocket, each of said loop portions having vertically spaced longitudinally extending arms extending into overlapping relationship with the sides of the straps of an associated draft gear yoke, the inwardly facing surfaces of said arms of each loop portion being spaced apart a distance 20 equal to the height of said base portion, a compensating follower at each end of said gear having a transverse portion for engagement with the adjacent abutment in an associated draft gear yoke, said compensating follower extending laterally between said arms of each loop portion and being movable longitudinally thereof, and a compensating cushioning unit at each end of said gear extending between said arms, said compensating unit reacting between said base of the associated 25 first-named follower and said compensating follower to oppose movement of the latter toward said base portion.

6. A draft gear for railway vehicles comprising a pair of longitudinally spaced followers, a cushioning unit extending between said followers and being compressible upon movement of one of said followers toward the other, each of said followers comprising a base portion in engagement with an end of said cushioning unit and a pair of rectangular loop portions extending longitudinally from said base portion and positioned to engage the stop lugs of a draft gear pocket, a compensating follower at each end of said gear movable longitudinally of said first-named follower, said compensating follower comprising a base portion extending into said loop portions of the associated one of said first-named followers and an abutment portion spaced from said base portion thereof and positioned to engage the adjacent abutment in a draft gear yoke, and a compensating cushioning unit extending between said base and abutment portions at each end of said gear for opposing movement of said compensating follower toward said base portion of said first-named follower, said compensating cushioning unit being carried by said loop portions.

7. A railway draft gear for assembly with a draft gear yoke and between the front and rear stop lugs of a draft gear pocket, comprising followers for engagement with said stop lugs, each of said followers having a base portion and rectangular loop portions extending therefrom toward the end of said gear, the ends of said loop portions being positioned to engage said stop lugs, resilient means compressed between said base por-

tions and urging the ends of said loop portions into tight engagement with said stop lugs, a compensating follower at each end of said gear having a transverse portion for engagement with the adjacent abutment in said yoke, said compensating follower being carried by said loop portions and being movable lengthwise thereof, and resilient means carried by said loop portions and reacting between said base portion of the associated one of said first-named followers and said compensating follower, said last-named resilient means being under predetermined initial compression for urging said compensating follower into engagement with the adjacent abutment in said yoke.

8. In a railway draft gear a pair of relatively movable followers, one of said followers comprising a transverse base portion and a pair of rectangular loop portions extending longitudinally from the lateral extremities of said base portion, the ends of said loop portions being positioned to engage the stop lugs of a draft gear pocket, and another follower having a base portion extending into said loop portions and being movable lengthwise thereof, said last-named follower having a draft gear yoke engaging portion spaced from said base portion thereof, and resilient means carried by said loop portions interposed between said base portions to oppose movement of said last-named follower toward said base portion of said first-named follower.

9. In a railway draft gear a pair of relatively movable followers, one of said followers comprising a rectangular base portion, arms extending longitudinally from the corners of said base portion, and vertical portions joining the ends of said arms, said vertical portions being positioned to engage the stop lugs of a draft gear pocket, and a draft gear yoke engaging follower extending between said arms and being movable lengthwise thereof, said last-named follower having a rectangular base portion of substantially the same length and width as said base portion of said first-named follower, and resilient means between said base portions for opposing movement of said last-named follower toward said base portion of said first-named follower.

10. In a railway draft gear a pair of relatively movable followers, one of said followers being U-shaped and comprising a transversely extending base portion and longitudinally extending side portions for engagement with the stops of a draft gear pocket, each of said side portions having rectangular transversely extending openings, another follower extending through said openings and being movable lengthwise of said side portions, said last-named follower having a transverse portion engageable with the adjacent abutment in a draft gear yoke, and resilient means between said base portion and said second-named follower for opposing movement of the latter toward said base portion.

11. A railway draft gear for assembly with a draft gear yoke and between the front and rear stop lugs of a draft gear pocket, comprising a central cushioning unit, followers engaging the ends of said unit and being of such extent longitudinally of said gear as to place said unit under initial compression when said gear is inserted between said stop lugs, said followers having spaced longitudinally extending loop portions the ends of which are positioned to engage said stop lugs, compensating followers extending into said loop portions and being movable lengthwise of said loop portions, said compensating followers being engageable with front and rear abutments in said

yoke, and compensating cushioning units extending into said loop portions, said compensating units being under initial compression to urge said compensating followers tightly against said yoke abutments.

12. A railway draft gear comprising a pair of relatively movable followers, one of said followers comprising a transverse base portion, vertical portions spaced longitudinally of said base portion and arms joining the upper and lower ends of said vertical portions to said base portion, said vertical portions being positioned to engage the stop lugs of a draft gear pocket, the other of said followers being engageable with an abutment in a draft gear yoke, said second follower facing said base portion and having lateral portions engageable with the inner sides of said vertical portions to limit movement of said second follower longitudinally away from said base portion, and resilient means for opposing movement of said second follower toward said base portion.

13. A railway draft gear comprising a pair of longitudinally spaced followers, each of said followers having a base portion and longitudinal side portions positioned to engage the front and rear stop lugs of a draft gear pocket, a group of resilient pads compressible between said base portions, said side portions having transverse openings, a compensating follower at each end of said gear having a transverse portion positioned to engage an abutment in a draft gear yoke, said follower being carried by the associated one of said first-named followers and being insertable therein transversely through said openings, and another group of resilient pads at each end of said gear between said compensating follower and said base portion to oppose movement of said compensating follower toward said base portion, said other group of resilient pads being insertable into said first-named follower transversely through said openings.

14. A railway draft gear for assembly with a draft gear yoke and between the front and rear stop lugs of a draft gear pocket, said gear comprising a central cushioning unit having end followers formed with longitudinal loop portions of such length as to place said unit under predetermined initial compression when said gear is assembled between said front and rear stop lugs, and other cushioning units at the ends of said gear, each of said other cushioning units being compressed between an adjacent one of said followers and an abutment in said yoke, said second-named cushioning units being under lesser initial compression than said central cushioning unit, said loop portions encircling said second-named cushioning units.

15. A railway draft gear for assembly with a draft gear yoke and between the front and rear stop lugs of a draft gear pocket, said gear comprising a central group of resilient pads having end followers formed with longitudinal loop portions of such length as to place said pads under predetermined initial compression when said gear is assembled between said front and rear stop lugs, each of said end followers comprising a transverse base portion engaging an end of said group of pads, and compensating groups of pads at the ends of said gear placed under predetermined initial compression between front and rear abutments in said yoke, said loop portions encircling said compensating pads, said compensating pads reacting between said base portion of the associated one of said end follow-

ers and the adjacent abutment in said yoke, said followers and said pads each being of substantially the same extent in a direction transversely of said gear.

16. A railway draft gear for assembly with a draft gear yoke and between the front and rear stop lugs of a draft gear pocket, said gear comprising a central cushioning unit, end followers engaging said unit, said followers being formed with longitudinal loop portions of such length as to place said unit under predetermined initial compression when said gear is assembled between said front and rear stop lugs, another cushioning unit at each end of said gear carried by said loops of each of said end followers, and a follower at each end of said gear extending into and carried by said loop portions, said second-named follower having a transverse portion positioned to engage the adjacent abutment in said yoke to place said second-named cushioning units under predetermined initial compression of a lesser amount than said central cushioning unit, said cushioning units and followers being so arranged that during initial actuation of said gear in either buff or draft one of said second-named cushioning units is compressed until the initial compression of said central unit is equaled after which said second-named cushioning unit and said central unit compress in series during the remainder of the actuation of said gear.

17. A follower member for a railway draft gear, comprising a transverse base portion and a pair of rectangular loop portions extending longitudinally from the lateral extremities of said base portion, the ends of said loop portions having stop lug engaging surfaces, said loop portions being formed with transverse openings for receiving associated resilient means of a draft gear.

18. A follower member for a railway draft gear, comprising a transverse base portion and a pair of rectangular loop portions extending longitudinally from the lateral extremities of said base portion, each loop portion comprising a pair of vertically spaced horizontal arms and a vertical element joining the ends of said arms, said loop portions being spaced apart to receive in overlapping relationship the upper and lower straps of a draft gear yoke, said vertical elements having surfaces for engagement with the stop lugs of a draft gear pocket.

19. In a railway draft gear a pair of relatively

movable followers, one of said followers comprising a transverse base portion and rectangular loop portions, said loop portions being spaced apart transversely and extending longitudinally from said base portion, said loop portions being joined by top and bottom walls, the ends of said loop portions having surfaces for engagement with the stop lugs of a draft gear pocket, said top and bottom walls being spaced apart a lesser amount than the straps of an associated draft gear yoke to enable insertion of said follower into said yoke by movement of said follower transversely into place between the yoke straps, and another follower carried by said loop portions having a surface for engagement with an abutment in said yoke, said other follower being insertable into said first follower transversely through said loop portions, and a cushioning unit carried by said loop portions and reacting between said base portion and said other follower to oppose movement of said other follower toward said base portion.

20. A railway draft gear comprising a forward follower and a rearward follower, a group of cushioning pads extending between said followers and being compressible therebetween, each of said followers having a pair of longitudinally extending loop portions for engagement with the stop lugs of a draft gear pocket, the loop portions of said forward follower being longer than the loop portions of said rearward follower, groups of cushioning pads extending into and carried by the loop portions of said followers said last-named groups of pads each being compressed between the associated one of said followers and an abutment in an associated draft gear yoke to maintain said draft gear in tight engagement with said yoke, the group of pads carried by the loops of said forward follower being of greater capacity than the group of pads carried by the loop portions of said rearward follower.

DONALD WILLISON.
